UNITED STATES PATENT OFFICE

2,087,998

FOUNTAIN PEN

Solomon M. Sager, Glencoe, Ill.

Application January 18, 1936, Serial No. 59,672

12 Claims. (Cl. 120—46)

This invention relates to a fountain pen and more particularly to a fountain pen filling unit for insertion in one end of a fountain pen barrel adjacent the inner end of an improved feed bar projecting into the opposite end of the pen barrel and extending through the fountain pen section and centrally through the barrel to within a short distance of the inner end of the filling unit.

10 It is an object of this invention to provide a fountain pen filling unit adapted to be conveniently mounted within one end of the fountain pen barrel to facilitate filling of the barrel.

15 It is also an object of this invention to provide a fountain pen feed bar unit including a grooved head portion which is adapted to be extended through a fountain pen barrel section and having the inner end thereof integrally connected up with an elongated shank of reduced or oval cross section adapted to extend into a fountain pen barrel to within a short distance of the pen filling unit.

20 It is a further object of this invention to provide a fountain pen with a filling device consisting of a separate casing having an apertured closed end and enclosing a bellows type filler provided with a stem which projects into an operating plunger slidably engaged in a closure bushing secured in the opposite end of the casing.

25 It is another object of this invention to provide a fountain pen with a filler unit adapted to be engaged as a unit in an end of an ordinary fountain pen barrel for the purpose of permitting easy filling of the barrel with ink.

30 Another object of the invention is to provide a fountain pen with an improved grooved feed member of one-piece construction including a head portion and a reduced shank portion which is comparatively long and is provided with a passage which connects up with a passage in the head section to afford an arrangement to replace the present type of feed mechanism which consists of a feed bar and a separate flexible intake tube.

35 It is an important object of this invention to provide a fountain pen including a body or barrel having a one-piece feed bar unit projecting through the pen section and having a long reduced shank portion formed on the inner end of the head portion of the feed bar and extending to within a short distance of the inner end of a filler unit engaged in the opposite end of the barrel and comprising a separate casing containing a bellows-like filler operable by

means of a plunger projecting from the filler casing and normally enclosed by means of a cap.

40 Other and further important objects of this invention will be apparent from the disclosures in the specification and the accompanying drawing.

This invention, in a preferred form, is illustrated in the drawing and hereinafter more fully described.

45 On the drawing:

Figure 1 is a central longitudinal section of an improved fountain pen embodying the principles of this invention and clearly illustrating the improved filler unit and the elongated feed bar member in cooperating relation.

Figure 2 is an elevational view of the filler unit removed from the fountain pen barrel and having the closure cap omitted.

Figure 3 is an end view of the inner or bottom end of the filler unit.

Figure 4 is a top elevational view of the feed bar unit removed from the fountain pen.

Figure 5 is an inner end view of the feed bar unit illustrating the reduced oval construction of the shank portion of the feed bar unit.

Figure 6 is a central longitudinal section of one end of a fountain pen including a modified form of filler unit and using an apertured washer in the base portion of the bellows mechanism.

50 As shown on the drawing:

The reference numeral 1 indicates a fountain pen body or barrel open at both ends. Engaged in one end of the barrel 1 is a section 2 having secured therein a pen point 3 secured between the section 2 and an improved elongated one-piece feed bar unit comprising a head or main body portion 4 of substantially circular cross section having one end thereof shaped and tapered to provide a tip portion 5. Integrally formed on the inner end of the head portion 4 is a long shank 6 of reduced oval cross section. The one-piece feed bar is provided with ink ducts or grooves 7 extending longitudinally of the feed bar from the end of the tip portion 5 to the end of the shank 6 for insuring a continuous constant flow of ink from the fountain pen, when in use, at all levels of the ink in the barrel and obviating the clogging up of the ink flow at the inner end of the section 2 by the formation of ink bubbles as often occurs in the use of short feed bars. The feed bar unit is provided with an intake passage 8 which extends from the end of the reduced feed bar shank 6 centrally therethrough into the head 55

portion 4 where it connects up with a radially directed passage arm 9 the outer end of which communicates with the ink feed ducts or grooves 7.

5 Removably engaged over the section end of the fountain pen is a main closure cap 10 which encloses the projecting tip end 5 of the feed bar unit and the pen point 3 to protect the same when the fountain pen is not in use.

10 Frictionally fitted or otherwise secured in the end of the fountain pen barrel opposite the section 2 is an improved fountain pen filler unit for use in combination with the improved feed bar as illustrated in Fig. 1 or if preferred the filler unit 15 may be sold separately and engaged in one end of a fountain pen barrel of any selected make, such for example as the type using an ordinary feed bar and an ink intake tube connected with the feed bar and projected upwardly into the 20 barrel.

The improved fountain pen filler unit comprises a casing or housing 11 open at one end and closed by means of an end wall 12 opposite the open end. The end wall 12 is provided with a small central 25 aperture 13. Fitted into the casing 11 against the inner face of the closed end 12 is a flexible filler mechanism for drawing up ink through the long intake shank 6 of the feed bar. The filler mechanism comprises a double bulb like rubber bellows 14 open at one end and communicating with an opening 15 provided in a packing base or flange like bottom 16 which tightly fits into the closed end of the casing 11 and seats against the inner face of the bottom 12 with the opening 15 30 in communication with the small opening 13 in the base of the case 11. The double barrel bulb bellows 14 is closed at its outer end and has integrally formed thereon a rubber stem 17. The stem 17 projects into a filling plunger 18 which is 35 closed at its outer end while the inner open end is provided with a flange 19. The plunger 18 is rotatably engaged on the stem of the bellows 14 and slidably projects through a passage in a flanged closure bushing 20 which is tightly secured 40 in the open end of the casing 11. The bushing 20 has integrally formed thereon an outwardly projecting exteriorly threaded neck 21 for the reception of a removable plunger enclosing cap or hood 22.

45 50 The complete filler unit as illustrated in Fig. 2 is rigidly secured in the outer end of the fountain pen barrel 1, which is provided with a shoulder at 23 against which the closed end 12 of the filler case 11 is adapted to seat. The flange of the bushing 20 fits against the outer end of the barrel 1 to complete the insulation of the filler unit in the fountain pen barrel.

To fill the fountain pen barrel 1 with ink the cap 10 is removed and the pen point and the end 5 of the feed bar is projected into a supply of ink. The protecting cap 22 is now removed from the bushing neck 21 thereby exposing the filling plunger 18 which may be repeatedly operated inwardly to cause a suction at the inner 60 end of the reduced shank portion 6 of the feed bar thereby causing ink to be drawn upwardly through the intake passages 9 and 8, and out into the ink containing chamber of the barrel 1 to fill the fountain pen. The resiliency of the double bulb bellows 14 when compressed causes the plunger 18 to be projected outwardly into its normal position after each inward movement thereof during the operation for filling the fountain pen.

70 75 Fig. 6 illustrates a modified form of a fountain pen filling unit in which the parts which are

identical with those described in connection with Fig. 1 are similarly designated. The modified form of filler unit comprises a separate housing or casing 24 open at the outer end and provided with an inwardly directed flange 25 at the 5 inner open end of the casing. The filling mechanism which is engaged in the casing 24 comprises a double bulb-like rubber bellows 26 consisting of a lower or smaller bulb section open at both ends, and a larger upper bulb portion closed at 10 one end and provided with a stem 27 which projects into the operating plunger 18, similar to the arrangement illustrated in Fig. 1. Integrally formed on the end of the small bulb section of the bellows member 26 is an internally grooved 15 packing base 28 provided with a bottom opening 29. Seated in the groove of the base 28 to expand the same into a tight seal with the interior of the casing 24 is a closure disk or plate 30 having a center cup or boss which is provided 20 with a plurality of small apertures 31 in the side walls thereof for distributing the discharge of air in small jets from the filler mechanism when the bellows member 26 is collapsed. The casing 24 of the filler unit is frictionally fitted into the open 25 end of the barrel 1 with the casing flange 25 seated against the shoulder 23 provided in the barrel 1. The bushing 20 through which the operating plunger 18 slidably projects is threaded or otherwise secured in the outer end of the casing 24 30 and has the flanged portion thereof seated against the outer end of the barrel 1 to complete the installation of the filler unit. The operation of the modified form of filler unit is substantially 35 the same as the operation of the filler unit illustrated and described in connection with Figs. 1 to 5 inclusive.

The fountain pen is of a simplified form in which the pen barrel has the pen point and the improved elongated feed bar engaged in one end 40 of the barrel while in the opposite end of the barrel the filler unit is installed in cooperating relation with the inner end of the reduced shank portion 6 of the feed bar. While the improved feed bar and the filler unit are used in combination in the form of the fountain pen illustrated in Fig. 1, it will of course be understood that the important part of the invention is the provision of the filler unit as illustrated in Fig. 2 and including the filler unit cap 22 which may be conveniently installed in different makes of fountain pen barrels to serve as a filling medium with a feed bar of the type described in this case or with the ordinary type of feed bar or the feed bar used in combination with a flexible intake tube. 55

It will of course be understood that various details of construction may be varied through a wide range without departing from the principles of this invention and it is therefore not the purpose to limit the patent granted hereon otherwise than necessitated by the scope of the appended claims.

I claim as my invention:

1. A fountain pen comprising an elongated barrel having an annular seat formed in one end 65 thereof, a section at the opposite end of the barrel, a pen point and a feed bar secured in the section, said feed bar having an elongated reduced shank extending through the barrel to within a short distance of the annular seat, a 70 filler unit engaged in the opposite end of the fountain pen barrel and seated on said seat, said filler unit comprising a casing having an apertured bottom seated against said seat, a resilient bulbous structure of rubber or the like seated in 75

the casing, a stem integrally formed on the bulbous structure, a hollow plunger engaged over the stem and provided with a flange seated against the bulbous structure, a bushing secured 5 in the open end of said casing and also seated against the end of the fountain pen barrel with the stem and the hollow plunger projecting through said bushing to expose the end of the plunger to permit operation of the bulbous structure to cause filling of the fountain pen through the feed bar, and a cap removably engaged on the bushing to enclose the hollow plunger after a filling operation of the fountain pen.

2. A fountain pen comprising a barrel having 15 a section engaged in one end thereof, a pen point in the section, a feed bar in the section in contact with the pen point and including a reduced passaged shank which extends into the fountain pen barrel to within a short distance of the end 20 of the ink chamber of the fountain pen barrel, and a filler unit secured in the outer end of the fountain pen barrel and including an apertured casing, a bulbous structure in said casing, an operating plunger engaged with the bulbous 25 structure and slidably projecting out of one end of the casing to permit operation of the bulbous structure to cause filling of the fountain pen, and a cap removably engaged on the casing to enclose the operating plunger after a filling operation.

3. A fountain pen comprising a barrel having a section engaged in one end thereof, a pen point in the section, a feed bar in the section in contact with the pen point and including a reduced passaged shank which extends into the fountain pen barrel to within a short distance of the end of the ink chamber of the fountain pen barrel, a 35 filler unit secured in the outer end of the fountain pen barrel and including an apertured casing, a bulbous structure in said casing, an operating plunger engaged with the bulbous structure and slidably projecting out of one end of the casing to permit operation of the bulbous structure to cause filling of the fountain pen, a cap removably 40 engaged on the casing to enclose the operating plunger after a filling operation, and a main cap for removal engagement over the section end of the fountain pen barrel to enclose the pen point and the projecting end of the feed bar when the 45 fountain pen is not in use.

4. In a fountain pen, a filler unit comprising a casing for insertion in one end of the fountain pen barrel, a bulbous rubber-like structure open at one end and closed at the opposite end disposed 55 in the casing, a base flange integrally formed on the open end of the bulbous structure, a stem on the closed end of the bulbous structure and projecting out of the casing, an operating plunger slidably engaged in the casing over said stem 60 and projecting from the casing to permit operation of the bulbous structure for filling the fountain pen.

5. In a fountain pen, a filler unit comprising an apertured casing secured in one end of the fountain pen barrel, a bushing for closing one end of the casing, a bulbous structure in the casing open at one end and closed at the opposite end, a stem integrally formed on the closed end of the bulbous structure and projecting outwardly through the bushing, an operating plunger rotatably engaged on the stem and slidably projecting through the bushing to permit operation of the bulbous structure for filling the fountain pen, and a cap 70 removably engaged on the bushing to enclose the

operating plunger when the filler unit is not in use.

6. In a fountain pen, a filler unit comprising a casing closed at one end and open at the opposite end and secured in the barrel of the fountain pen, 5 said closed end of the casing having an aperture therein, a bulbous structure seated in the casing open at one end and closed at the opposite end, an apertured packing base at the open end of the bulbous structure seated against the apertured closed end of the casing, a stem integrally formed on the closed end of the bulbous structure and projecting from the casing, a bushing engaged in the open end of the casing to close the casing and the fountain pen barrel, a plunger 10 engaged over the stem and slidably projecting through the bushing, a flange integrally formed on the plunger seated on the closed end of the bulbous structure and engaged against the inner end of the bushing to hold the plunger against 15 removal from the bushing, and a cap removably engaged on the bushing for enclosing the projecting end of the plunger.

7. In a fountain pen, a filler unit comprising a casing open at one end and having an apertured base at the opposite end, said casing secured in one end of the fountain pen barrel, a bushing secured in the open end of the casing and having a flange seating against the end of the fountain pen barrel, a bulbous rubber-like 20 structure engaged in the casing closed at one end and having an apertured packing base at the opposite end in sealing contact with the inner wall of the casing and with the apertured base of the casing, a stem integrally formed on the closed end of the bulbous structure and projecting outwardly through the bushing, a flanged plunger engaged on the bulbous structure over 25 said stem and slidably projecting through the bushing into a position to permit operation of the bulbous structure for filling the fountain pen barrel, and a closure removably engaged on the bushing for enclosing the plunger when the same 30 is not in use.

8. In a fountain pen, a filler unit comprising a casing removably secured in one end of the fountain pen barrel, a bulbous rubber-like structure in the casing, and plunger means seated on the bulbous structure and projecting from the casing to permit operation thereof to cause 45 application of pressure to the bulbous structure.

9. In a fountain pen, a filler unit comprising a casing adapted to be removably secured in one end of a fountain pen barrel, a bulbous rubber-like structure in the casing, a grooved packing base integrally formed on one end of the bulbous structure, an apertured disk seated in the grooved base to expand the same into sealing contact with the interior of the casing, a stem integrally formed on the opposite end of the bulbous structure and projecting from the casing, and an operating plunger rotatably contacting the bulbous structure and enclosing said stem and slidably projecting from the casing to 55 permit operation of the bulbous structure.

10. A fountain pen including in combination a filler unit comprising a casing, a rubber-like filling means engaged in the casing and comprising a bulbous portion, a bellows-like section integrally formed on one end of the bulbous portion, an apertured base connected with the bellows-like portion, a stem integrally formed on the bulbous portion and projecting from the casing, and an operating plunger seated on the bulbous 60 portion.

ous portion and enclosing said stem, said operating plunger slidably projecting from the casing into a position to permit operation of the bulbous structure within the casing.

5 11. A fountain pen filling unit comprising a casing, a hollow plunger slidably projecting from the casing closed at one end and having a flange formed on the inner end to prevent removal of the plunger from the casing, a bellows-like rubber structure engaged in the casing, a stem integrally formed on the bellows-like rubber structure and projecting into the plunger, a grooved packing base formed on the bellows-like rubber structure, and an apertured disk engaged in the

grooved base to expand the same into a tight sealing fit with the interior of the casing.

12. In a fountain pen including in combination a filling means comprising a large main bulb portion open at one end and closed at the opposite end, a stem on the closed end of the main bulb portion, a smaller bulb section integrally formed on the open end of the large bulb portion, an internally grooved apertured base integrally formed on the small bulb section, and a 10 disk seated in the groove of said base and having a cup-shaped portion provided with a plurality of air escape apertures in the side walls thereof.

SOLOMON M. SAGER.
